[57] ABSTRACT

A multistage throttle valve has a generally cylindrical housing with an inlet adjacent one end and an outlet at the other end. The interior of the housing is spanned by several, axially spaced valve seat plates having coaxial apertures therethrough of progressively larger sizes toward the outlet. An axially movable operating rod passes axially through the apertures and carries at least one of several valve discs thereon. An operating tube is disposed around the operating rod and carries the valve discs not carried by the rod. The tube is movable axially along the rod and can be fastened thereto.

MULTISTAGE THROTTLE VALVE

The multistage throttle valve of this application is of the same general sort disclosed in the copending application of Thomas C. Jester et al., Ser. No. 635,191, filed May 1, 1967, now U.S. Pat. No. 3,515,370, and assigned to the assignee hereof.

In the operation of hydraulic systems there is often the requirement of reducing the pressure of a flowing stream of liquid, usually water, and under some circumstances it is desirable to reduce the pressure not simply in one stage but rather in several stages. The amount of reduction at one stage preferably bears some relationship or proportion to the reduction at another stage. The arrangement can be well calculated for a fixed range of conditions in order to have precisely the designed ratio of throttling per stage. Under some circumstances the conditions change markedly from time to time or vary substantially without previous notice. It may then be preferred to reduce the pressure by means of a different number of throttling stages or in different amounts per stage.

It is therefore an object of the invention to provide a multistage throttling valve which even after installation can be varied to suit the particular conditions of operation then obtaining.

A further object of the invention is to provide a multistage throttling valve in which the number of effective stages can be changed from time to time.

Another object of the invention is to provide a multistage throttling valve in which the relationship between the different throttling stages can be changed by an operator at will.

Another object of the invention is to provide a multistage throttling valve in which different ones of the throttling mechanisms can be utilized for shutoff.

A further object of the invention is to provide a multistage throttling valve which, particularly in medium and smaller sizes, can readily be actuated by hand.

A still further object of the invention is to provide an improved and more versatile multistage throttling valve.

Other objects together with the foregoing are attained in the embodiments of the invention described in the accompanying description and illustrated in the accompanying drawings, in which:

FIG. 1 is a cross section on a transverse longitudinal plane through the axis of one form of multistage throttling valve constructed pursuant to the invention;

FIG. 2 is a fragmentary cross section like FIG. 1 but showing the throttling mechanism in a different position; and

FIG. 3 is a modification of the multistage throttling valve showing a different construction but with the parts approximately in the position of operation shown in FIG. 1.

Although the throttling valve pursuant to the invention can be employed in a large number of different configurations and can be installed in various different environments, it is illustrated herein as it is designed and installed in a typical case.

In this instance the multistage throttling valve includes a housing 6 generally of circular cylindrical configuration outside and inside and symmetrical about a through or flow axis 7. The housing adjacent one end has an inlet tube 8 terminating in a flange 9 for connection to a supply pipeline of any desired sort. Adjacent the other end and in effect continuing the outlet 11 of the housing is an adapter 12 having a flange 13 designed for connection by fasteners 14 to the outlet flange 16 of the valve housing. The adapter 12 has its own outlet 17 leading to any suitable downstream connection.

The interior of the housing 6 is partially divided by a number of valve seat plates 21, 22 and 23. These are spaced apart axially at desired locations and each of them is characterized by a respective one of a number of central flow openings 26, 27 and 28. The openings are concentric with the axis 7 and vary in size becoming progressively larger as they approach the outlet 11. The particular axial location and area or size of each of the openings is designed to meet the particular conditions of service of the valve. There is usually a fixed or a predetermined ratio or proportion between the areas of the successive openings. All of the openings are preferably

finished to provide seat surfaces 29, 31 and 32 for cooperation with a respective one of a series of valve discs 33, 34 and 36. The valve discs are configured to have mating surfaces 37, 38 and 39 designed to abut with the respective seat surfaces 29, 31 and 32 provided that the positioning mechanism for the valve discs is appropriately actuated.

In accordance with the invention, at least one of the valve discs is supported individually and for operation independently of the others. For example, in the present instance the valve discs 34 and 36 are formed as portions of an integral or unitary member 40. Included therein is a central boss 41 connecting the valve discs directly and a tail boss 42 machined to move axially within a bushing 43 carried by a spider 44 having a rim 46 clamped in position near the outlet 11. In this fashion the downstream portion of the assembly of the discs is appropriately guided. The disc member 40 likewise carries an upstream boss 47 connected by threads 48 to an operating rod 49 extending axially along the housing 6. The connection between the rod 49 and the valve disc member 40 is preferably secured by a pin 51.

The rod 49 at its upstream end is somewhat enlarged and is provided with a threaded portion 52 readily engaged by a threaded actuating nut 54 designed to turn about the axis 7 in a frame 56 having a yoke 57 secured firmly to the housing 6. The nut 54 is confined within the housing 56 by a pair of thrust bearings 58 and 59 so that the nut can turn readily but cannot move axially. The nut 54 includes a threaded portion 61 of its own which carries a handwheel 62 or other convenient actuator secured in position by a fastener 63. In addition, the threaded portion 61 carries a locknut 64 with an operating wing 66.

When the locknut 64 is released by manipulation of the wing 66, the handwheel 62 can be turned in either direction. The nut 54 thus is effective to move the operating rod 49 either to the right or to the left in FIG. 1 provided the operating rod is prevented from turning. For this reason a keyway 67 extends along the operating rod. The bearing end 68 of a screw 69 projects into the keyway and is held in position by its own locknut 71. With the mechanism as so far described, rotation of the handwheel 62 produces an axial translation of the operating rod 49 and thus moves the valve discs 34 and 36 toward and away from their respective seats. The arrangement is preferably such that the discs are slightly farther apart or closer together than the seats so that when one of them is seated the other is off of its seat.

Particularly pursuant to the present invention, the valve disc 33 is not part of the disc member 40 but rather is separately arranged. The upstream valve disc 33 is carried by an operating tube 72 surrounding the operating rod 49 and coaxial therewith. There is an O-ring 73 or other comparable seal between the operating tube 72 and the operating rod 49. The operating tube 72 at its upper or left-hand end (in FIG. 1) is enlarged to provide in effect a nut 74 engaging a part of the threaded portion 52 of the operating rod 49. Since sometimes it is desired to utilize different materials for different parts, the nut 74 is extended and encased in a bearing sleeve 76. This is secured to the nut by a number of machine screws 77 so that the two parts operate in unison. To preclude any leakage the space between the sleeve 76 and the nut 74 is sealed by an O-ring 78. The sleeve 76 is reciprocable and rotatable within a flanged bushing 79 mounted in the body 6 and held in position by fastening screws 81. A number of depressions 82 in the sleeve 76 are in positions to receive a spanner wrench or the like so that the nut 74 can be manually rotated.

Under some circumstances it is desired to lock the nut 74 and the operating rod 49 so that they cannot be moved with respect to each other. This is particularly desirable in at least two relative axial positions of these parts. For that reason the operating stem 49 has a pair of sockets 83 and 84 conveniently formed on opposite sides thereof and spaced apart a predetermined axial distance.

Carried by the sleeve 76 and designed to engage in either one of the sockets 83 or 84 is a plunger 86 manually operable

outwardly in a radial direction and normally urged inwardly by a spring 87. In one position the plunger occupies the depression 83, for example, and locks the operating tube 72 and the operating rod 49 together in one axial spacing or relationship.

In the operation of this mechanism, as so far described, the parts can be in the position shown in FIG. 1. In that position the seats 29 and 37 are in abutment so that there is no flow through the valve. When the actuator wheel 62 is rotated in the appropriate direction with the plunger 86 in position in the socket 83, both the actuating rod 49 and the actuating tube 72 necessarily travel in unison and the valve discs 33, 34 and 36 move simultaneously as the rotating nut 54 translates the threaded portion 52. The initial throttling then takes place between the seats 29 and 37 with subsequent throttling between the seats 31 and 38 and final throttling between the seats 32 and 39. The valve can be fully opened and then reclosed simply by rotating the wheel 62.

When the conditions change and it is desired to have only two-stage throttling rather than three-stage throttling, the operator then retracts the plunger 86. By the use of a spanner in the depressions 82, for example, he rotates the bearing sleeve 76 to screw the operating tube along the operating rod until such time as the valve disc 33 is in fully opened position. The valve disc 33 is then approximately or actually in abutment with the boss 47, substantially as shown in FIG. 2. With the parts in the new relative axial location, the plunger 86 can be introduced into the socket 84 again to lock the actuating tube and the actuating rod together for further unitary motion.

Under these circumstances, as shown in FIG. 2, the valve disc 33 always remains open and does no substantial throttling whereas the valve disc 34 then seats. When opened, the valve disc 34 does the initial throttling between the seats 31 and 38 with secondary throttling occurring between the seats 32 and 39.

At the conclusion of the double throttling operation the user can withdraw the plunger 86 and with a spanner in the depression 82 rotate the bearing sleeve 76 and the operating tube in the reverse direction until such time as the plunger 86 reengages the socket 83. The parts are then restored to their initial condition for three-stage throttling.

As a further variation in the arrangement there is shown in FIG. 3 a construction in which the operating rod 49' carries but a single throttling or valve disc 36' whereas the operating tube 72' carries a pair of throttling discs 33' and 34', the parts otherwise being in substantially the same relationship and operating in substantially the same way as above described. An exception is that when the discs 33' and 34' are displaced entirely to the right (in FIG. 3) with a close approach to the disc 36' then both the discs 33' and 34' are substantially fully opened at all times and but a single stage of throttling is provided by the disc 36' which then serves also as a tight closure.
